Des. 242,331
Patented Nov. 16, 1976

242,331

ELECTRONIC WEIGHING SCALE

Peter Kunz, Meilen, and Paul Kern, Hombrechtikon, Switzerland, assignors to Mettler Instrumente AB, Zurich, Switzerland

Filed June 3, 1975, Ser. No. 583,171

Term of patent 14 years

Int. Cl. D10—04

U.S. Cl. D10—91

Fig. 1

Fig. 2

Fig. 3

Fig. 4

Fig. 5

Fig. 6

FIG. 1 is a top right front perspective view of an electronic weighing scale showing our new design;

FIG. 2 is a bottom plan view thereof;

FIG. 3 is a front elevational view thereof;

FIG. 4 is a rear elevational view thereof;

FIG. 5 is a top plan view thereof; and

FIG. 6 is a left side elevational view thereof.

We claim:

The ornamental design for an electronic weighing scale, as shown.
